UNITED STATES PATENT OFFICE.

ARTHUR M. ST. CLAIR, OF KANSAS CITY, MISSOURI, ASSIGNOR TO JANSSEN-OSTERTAG MFG. CO., OF KANSAS CITY, MISSOURI, A CORPORATION OF MISSOURI.

POURING DEVICE.

Application filed May 9, 1921. Serial No. 467,809.

To all whom it may concern:

Be it known that I, ARTHUR M. ST. CLAIR, a citizen of the United States, and resident of Kansas City, county of Jackson, State of Missouri, have invented a certain new and useful Improvement in Pouring Devices, of which the following is a complete specification.

The present invention relates to attachments for cans or similar containers, and aims to provide an improved form of pouring device or extension, adapted to be conveniently attached to the pouring neck or outlet of the can or container for facilitating the operation of pouring out the liquid contents of the can.

Accordingly, the principal object of the invention is to provide an attachment of the character described in the form of an outlet extension adapted to be attached in communication with the pouring outlet of the can, and including a flexible type of element for forming the connection between said extension and the outlet neck of the can, in order to produce a more conveniently manipulated device for pouring purposes, as well as one that will withstand rough usage for a longer time than similar devices now in commercial use.

It is also sought to provide a pouring device of the character indicated in which provision is made for forming a suitable well or drip basin at one end of the attachment and surrounding the pouring outlet of the can, for the purpose of collecting and retaining any drippings which may remain between the pouring operations.

With these objects in view, the invention will now be described by reference to the accompanying drawing, illustrating one form of attachment which I have devised for embodying the proposed improvements, after which the novel features therein will be particularly set forth and claimed.

In the drawing—

Figure 1 is a plan view showing a portion of a can or container equipped with a pouring device or extension constructed in accordance with the present invention;

Figure 2 is a side elevation of the same, with the pouring extension shown in section;

Figure 3 is a sectional view, illustrating a section indicated by the line III—III of Figure 1;

Figure 4 is a plan view of the pouring device shown detached from the can or container;

Figure 5 is an enlarged detail section, taken on the line V—V of Figure 4.

In the drawing, I have illustrated the improved device as applied to a can or container 6 which may be of any common form, such as is usually provided with a pouring outlet passage 7 surrounded by a screw neck 8 adapted to be closed ordinarily by a screw cap 9, as shown in Figures 1 and 3. As an attachment for facilitating the pouring operation from the can 6, I provide a tapering extension 10 adapted to be constructed of light sheet metal formed with a marginal flange 12 for forming a pouring outlet or channel 13 from the outlet 7 to the outer or open end 14 of the extension. The inner or wider end of the extension is provided with an opening 15 of a size adapted to be fitted over the screw neck 8, and formed with an outturned flange 16, to the lower face of which flange 16 is adapted to be applied a ring or washer 17 of any appropriate flexible resilient material, such as rubber or rubberized fabric, and having a central opening 18 of a size adapted for snug-fitting engagement with the exterior of the screw neck 8. The flexible element 17 is adapted to be secured in engagement with the flange 16 by means of a channel collar 20 embracing both the flange 16 and ring 17 and securely clamped in this relation as shown in Figure 5.

The improved construction as above described provides a pouring device having a flexible form of connection with the screw neck 8 of the can or container 6, whereby the device may be readily and conveniently applied to the can outlet and shifted into different positions thereon by simply sliding the device back and forth upon the screw neck, as required between pouring operations. For example, the device is simply slipped upon the screw neck 8 and to the base thereof, as shown in Figure 3 and the cap member 9 screwed down upon the neck 8 above the pouring device, as shown in Fig-

ures 1 and 3. When not in use, the outer projecting end of the extension 10 will of course be turned inward over the top of the can 6.

5 In the operation of pouring, the cap member 9 is detached, and the extension 10 swung around into outwardly projecting position as shown in Figures 1 to 3, and slipped upward along the screw neck in 10 proximity to the outer end of the neck 8, as shown in Figure 2, in order that the liquid contents may be properly deflected into the pouring channel 13 of the device 10, as will be readily understood. Between 15 pouring operations, the device is of course restored to its original position for permitting the application of the screw cap 9. As ordinarily constructed these pouring devices are usually made of one piece of metal, with 20 the neck engaging portion integral with the extension 10, and the objection found to these has been that the shifting movement of the extension along the screw neck and turning the device into and out of projecting 25 relation to the can, gradually distorts the neck-engaging opening in the extension, so that the same no longer fits the screw neck 8, and a leaky construction results and the pouring device finally becomes so worn 30 and out of shape as to be practically useless. The present construction overcomes these disadvantages, and affords several new features of utility. The flexible ring or washer 35 17 provided for connecting it with the screw neck affords a tight and snug-fitting joint, while permitting the extension to be moved readily up and down along the screw neck 8, and without any appreciable wear or any permanent distortion of the opening 18 embracing the neck portion 8. The flexible 40 and yielding character of this ring or washer 17 causes it to so embrace the screw neck as to not only produce a non-leaking connection, but also insures the retention of the 45 pouring device in proper position at any point upon the neck 8 to which it may be set, which is not the case with the all-metal construction particularly after the latter has become somewhat worn. It will also be noted that the ring or washer 17 may also 50 function as a washer or gasket where the relative lengths of the screw neck and cap member 9 are such as to permit the screwing of the latter tightly down upon the element 55 17, with said element at the base of the screw neck 8. Finally, the construction of the flanged opening 15 and parts connected therewith is such as to form in effect a well or drip basin within said opening 15 and

above the ring 17, for the collection of any 60 drippings which may be returned by the channel 13 between pouring operations, as is obvious.

While I have shown and described what I now regard as the preferred form of construction, I desire to reserve the right to make such changes or modifications as may fairly fall within the scope of the following claims.

What I claim is:

70 1. An attachment for containers having a screw neck providing a pouring outlet, said attachment comprising an extension formed with an outlet or pouring channel, the inner end of said extension having an 75 annular flexible element of compressibly resilient material adapted for snug-fitting engagement with said screw neck.

2. An attachment for containers having a screw neck providing a pouring outlet, 80 said attachment comprising an outlet extension formed with a pouring channel, one end of said attachment being formed with an opening permitting application of said end of the attachment to said screw neck, said 85 opening being fitted with an inwardly projecting flexible resilient lip of partly rubber composition adapted for snug-fitting engagement with said screw neck.

3. An attachment for containers having 90 a screw neck providing a pouring outlet, said attachment comprising an outlet extension formed with a pouring channel, one end of said attachment being formed with a flanged opening permitting application of 95 the attachment of said screw neck, and a flexible ring element of compressibly resilient material supported by the flange of said opening and adapted for snug-fitting engagement with said screw neck.

4. An attachment for containers having a screw neck providing a pouring outlet, said attachment comprising an outlet extension formed with a pouring channel, one end of said attachment being formed with an 105 opening of somewhat larger diameter than said screw neck for permitting the latter to be received through said opening, and an annular flexible element of compressibly resilient material secured to said attachment 110 beneath said opening and adapted for snug-fitting engagement with said screw neck, and thereby forming a drip basin or collecting channel above said element and around said screw neck.

In witness whereof I hereunto affix my signature.

ARTHUR M. ST. CLAIR.
